UNITED STATES PATENT OFFICE.

GEORGE L. MORRIS AND WILLIAM T. WILSON, OF LONDON, ENGLAND.

VELOCIPED.

SPECIFICATION forming part of Letters Patent No. 460,242, dated September 29, 1891.

Application filed May 23, 1891. Serial No. 393,809. (No model.) Patented in England September 9, 1889, No. 14,205, and October 30, 1889, No. 17,215.

To all whom it may concern:

Be it known that we, GEORGE L. MORRIS and WILLIAM T. WILSON, both subjects of the Queen of Great Britain, residing in the city 5 of London, England, have invented certain new and useful Improvements in Velocipedes, (for parts of which we have been granted patents in Great Britain, Nos. 14,205 and 17,215, and dated, respectively, the 9th of September, 10 1889, and the 30th of October, 1889,) of which the following is a specification.

Our invention relates to that class of velocipedes having two equal or approximately equal sized wheels placed one in front of the 15 other, the front one being used for steering and the rear one for driving, such machines being technically known as "Safety bicycles," and its objects are, first, to provide a strong and rigid frame; secondly, to provide a simple 20 and easy method of adjusting the driving-chain; thirdly, to facilitate the adjustment of the ball-bearings wherever applied; fourthly, to facilitate the attachment of the driving-chain wheel and the cranks to the pedal-crank 25 axle, so that they may readily and easily be attached to or removed from the said axle, and, fifthly, to provide a means of attaching the pedal-pin to the crank, whereby the width of the "tread" may be materially reduced. 30 We attain these objects in the manner illustrated in the accompanying drawings, in which—

Figure 1, Sheet No. 1, is a view in side elevation of a Safety bicycle embodying our 35 improvements. Fig. 2, Sheet No. 1, is a perspective view in side elevation, on an enlarged scale, of the improved main frame. Fig. 3, Sheet No. 1, is a view in broken side elevation, on an enlarged scale, of the chain adjustment; and Fig. 4, Sheet No. 1, is a view in plan of the adjusting-bolt thereof. Fig. 5, Sheet No. 2, is a view in sectional elevation of a pedal-crank-axle bracket and its fittings, showing the improved method of adjusting 40 the ball-bearing and the improved method of attaching the cranks and the driving-chain wheel to the pedal-crank axle and the pedal-pin to the crank. Fig. 6, Sheet No. 2, is a broken view in end elevation of the pedal-crank 45 and axle with the washer and key removed, showing the keyway in the end of the axle and

the ends of the bosses of the chain-wheel and crank. Fig. 7 is a broken view in end elevation, showing the method of attaching the pedal-pin to the crank. Fig. 8, Sheet No. 2, 55 is a view in end elevation of the adjustable clip of the ball-bearing; and Fig. 9, Sheet No. 2, is a broken view in side elevation showing the application of the improved adjustment to a ball-bearing head. Figs. 10 and 11 are 60 broken views in end and side elevation of a modification of our improved method of attaching the cranks and chain-wheels to the pedal-crank axle; and Fig. 12, Sheet No. 2, is a broken view showing a further modification 65 of this part of our invention.

Throughout these several views similar parts are marked with like letters and figures of reference.

Referring to Figs. 1 and 2 of the accompanying drawings, the main frame A consists of eight essential parts, which are designated by numbers. 1 and 2 are forks, the prongs of which are joined together and slotted to form small forks a to receive the axle B of the 70 driving-wheel. The crowns of these forks are connected by a segmental tube 3. From the junction of the fork 2 and the segmental tube 3 a tube 4 runs forward and upward and is joined to the lower end of the socket 5, 75 forming part of the steering head or joint. From the junction of the fork 1 and the segmental tube 3 a tube 6 runs forward and is joined to the top of the socket 5. From the junction of the fork 1 and the segmental tube 80 85 4 a short vertical tube 7, adapted to receive the stock of the seat-pillar, and across the angle formed by the tube 7 and the tube 6 a diagonal stay 8 is fixed. The bracket for carrying the bearings for the 90 pedal-crank axle is located at the junction of the fork 2 and the tube 4. A frame constructed on these lines may be made of tube of exceeding light gage, as its members are so arranged as to give the greatest rigidity 95 and strength to the whole structure.

Referring to Figs. 3 and 4, Sheet No. 1, of the accompanying drawings, in the small forks formed on the ends of the combined prongs of the forks 1 and 2 of the frame A 100 are cut or formed slots a', adapted to receive the ends of the axle B, carrying the driving-

wheel. On each end of the axle B is placed a washer C, having a screwed shank c set off to lie within the slot h' . On this screwed shank is threaded a nut D, having a collar or rim d formed on it, adapting it to engage with slots or recesses a^2 , formed in the prongs of the fork a. The nut D may be formed with a square or hexagon head to enable it to be turned with a spanner, or it may be made with wings, forming a butterfly-nut, or the head may be simply milled to enable it be turned by hand. To adjust the tension of the driving-chain, the lock-nuts b b on the ends of the axle B are slackened and the adjusting-nuts D D rotated equally, thus imparting travel to the screwed shanks c c of the washers C C, and so altering the position of the axle B. After the necessary adjustment has been effected, the lock-nuts b b are tightened and the axle and washers locked tightly to the frame A.

Referring to Figs. 5, 8, and 9 of the accompanying drawings, we form on the outside of the adjustable cone E of a ball-bearing a split sleeve E', having lugs or ears ee, through one of which a screw e' passes and is threaded into the other. Round the sleeve E' at its point of attachment to the cone E and for about half its circumference we cut or form a slot e^2 , the said slot being at right angles to the slot e^3 , formed between the lugs or ears e e of the sleeve E'. By reason of the two slots e^2 and e^3 the sleeve may be contracted by means of the screw e' to grip the axle or spindle on which the combined cone and sleeve is threaded, thus dispensing with the nut usually used to lock the cone after adjustment.

Referring to Figs. 5, 6, 10, and 11 of the accompanying drawings, the crank F is fixed 40 to the pedal-crank axle G by means of a key H, adapted to fit in a transverse keyway or slot h , cut or formed across the end of the axle and the boss of the crank. To keep the key H in position, a screw g is threaded into 45 the end of the axle and may either bear directly on the key H, through a washer H', as shown by Fig. 5, or directly, as shown by Fig. 11. The key H and keyway h may be either made with parallel sides, as shown by Figs. 5 and 6, or slightly tapered, as shown by Figs. 10 and 11. The washer H' may be made in one piece with the key H, as shown by Fig. 12. We fix the end of the pedal-pin J to the free end of the crank F by a key H, in the same manner that the crank is fixed to the 55 pedal-crank axle, as shown by Figs. 5 and 7.

When it is desired to make the driving-chain wheel K easily detachable, it is formed with an elongated boss or sleeve k, over 60 which the crank F fits, and both are then fixed to the axle G and to each other by the key H, as hereinbefore described, as shown by Fig. 5 of the accompanying drawings. Fig. 12 shows a modification of this arrangement, in which the abutting faces of the bosses of the chain-wheel K and crank F are "halved" together and kept interlocked by

the key H, which fixes the crank to the axle, as hereinbefore described.

We wish it to be particularly understood 70 that we do not limit ourselves to the exact details of construction hereinbefore set forth and illustrated by the accompanying drawings, but hold ourselves at liberty to make such changes and alterations as fairly fall 75 within the spirit and scope of our invention.

We are aware that it is not new to make the main frame of a Safety bicycle of a diamond pattern nor to adjust the driving-chain by moving the axle of the driving-wheel in 80 slots in the main frame, nor to make the cranks and chain-wheel detachable from the pedal-crank axle, and we do not claim these broadly; but

What we do claim as our invention, and desire to secure by Letters Patent, is—

1. In the main frame of a velocipede, the combination of the tubular forks 1 and 2, adapted to carry the axle of the driving-wheel, of the single segmental tube 3 joining the 90 crowns of the said forks 1 and 2, of the vertical tube 7, springing from the junction of the fork 1 and the segmental tube 3, of the steering-socket 5, of the single tube 4, connecting the crown of the fork 2 with the bottom of the steering-socket 5, of the single tube 6, connecting the crown of the fork 1 with the top of the steering-socket 5, and of the diagonal stay or brace 8, connecting the top 95 of the tube 7 with the tube 6, all combined, 100 arranged, and operating as set forth.

2. In a velocipede-frame, the combination, with the slots a' a' , adapted to receive the axle B of the driving-wheel, of the washers C C, adapted to fit over the ends of the axle 105 B and bear against the sides of the slotted ends of the frame, of the screwed shanks c c, carried by the washers C C and cranked to enable them to lie within the slots a' a' in the frame, and of the nuts D D, threaded on the 110 screwed ends of the shanks c c and having flanges or lips d d, adapted to engage with recesses or slots a^2 a^2 in the sides of the slots a' a' , all combined, arranged, and operating as and for the purpose set forth. 115

3. In a velocipede, the combination, with the adjustable cone E of a ball-bearing, of the split sleeve E', forming part of the said cone, but divided from it for about half its circumference by the slot e^2 , at right angles to the slot e^3 , formed between the ears or lugs e e on the sleeve E', and of the screw e', adapted to draw the two ears or lugs ee together, all combined, arranged, and operating as and for the purpose set forth. 120

4. In a velocipede, the combination, with the pedal-crank axle F and the crank G, of the key H, the transverse keyway or slot h , formed across the end of the axle and the face of the boss of the crank, and of the screw g, 130 adapted to hold the key in position, all combined, arranged, and operating as and for the purpose set forth.

5. In a velocipede, the combination, with

the pedal-crank axle F and the crank G, of the key H, the washer H', the keyway or slot h, and the screw g, all combined, arranged, and operating as and for the purpose set forth.

5 6. In a velocipede, the combination, with the crank G and the pedal-pin J, of the key H, and the screw g, all combined, arranged, and operating as and for the purpose set forth.

7. In a velocipede, the combination, with 10 the crank G and the pedal-pin J, of the key H, of the washer H', and of the screw g, all combined, arranged, and operating as and for the purpose set forth.

8. In a velocipede, the combination of the 15 chain-wheel K, having an elongated boss k, adapted to fit on the pedal-crank axle G, of the crank F, adapted to fit over the boss k of the chain-wheel K, of the keyway or slot h, cut or formed across the end of the axle and 20 the faces of the bosses of the chain-wheel and crank, of the key H, adapted to fit in the said keyway or slot, and of the screw g, adapted to hold the key H in position, all combined, arranged, and operating as and for the 25 purpose set forth.

9. In a velocipede, the combination of the 30 chain-wheel K, having an elongated boss k, adapted to fit on the pedal-crank axle G, of the crank F, adapted to fit over the boss k of

the chain-wheel K, of the keyway or slot h, 30 cut or formed across the end of the axle and the faces of the bosses of the chain-wheel and crank, of the key H, adapted to fit in the said keyway or slot, of the washer H', adapted to bear against the said key, and of the screw 35 g, adapted to hold the key H in position, all combined, arranged, and operating as and for the purpose set forth.

10. In a velocipede, the combination of the chain-wheel K, of the crank F, the abutting 40 faces of the bosses of which are halved together so as to interlock the two together, and of the transverse key H, with attached washer H', adapted to fit in a transverse slot or keyway h, cut across the end of the axle G and 45 the face of the boss of the crank F, all combined, arranged, and operating as and for the purpose set forth.

In witness whereof we have hereunto signed our names in the presence of two subscribing 50 witnesses.

GEORGE L. MORRIS.
WILLIAM T. WILSON.
